UNITED STATES PATENT OFFICE.

WILLIAM K. MEYER, OF BROOKLYN, NEW YORK, ASSIGNOR TO MEYER, BACHARACH AND FRIEDHEIM, OF NEW YORK, N. Y., A FIRM COMPOSED OF WILLIAM K. MEYER, ROBERT L. BACHARACH, AND ARTHUR FRIEDHEIM.

FOUR-IN-HAND SCARF OR NECKTIE.

1,127,485.

Specification of Letters Patent.

Patented Feb. 9, 1915.

Application filed May 19, 1914. Serial No. 839,485.

To all whom it may concern:

Be it known that I, WILLIAM K. MEYER, a citizen of the United States, residing at Brooklyn, in the county of Kings and State of New York, have invented certain new and useful Improvements in Four-in-Hand Scarfs or Neckties, of which the following is a specification.

This invention relates more especially to improvements in that class of scarfs or neckties which are worn tied in a four-in-hand knot, and its objects are to provide means for preserving the scarf or tie against injurious pulling action on the outer or 15 ornamental material and to minimize as far as possible any necessity to grasp with the hands such portion of the scarf or tie either in adjusting it on the collar or in actually 20 tying the knot, and to provide a scarf or tie which may be more readily adjusted on any kind of collar.

One of the quickest ways to injure a scarf or four-in-hand tie, particularly those cut on the bias, is to pull on the outer or ornamental material in adjusting it on the collar before tying the knot, and also in adjusting the knot in its proper position. With a turn over collar this is especially true, since the scarf sticks or becomes bound in such a way that considerable force is often necessary to make the scarf slip longitudinally on the collar. Also, with any kind of collar it is necessary to hold the under end of the scarf while the knot is being tied and this exerts an injurious tension on the outer material if this be grasped as it usually is in this operation. Again, in tightening the knot another pull is usually made on the outer end of the scarf which, if applied to the outer or ornamental material, further tends to injure it. My improvement makes it entirely unnecessary to exert any pull on the outer material of the scarf in any such cases. In fact, a scarf provided with my improvement may be practically completely tied without grasping the ornamental or outer material at all. Furthermore, my improvement makes the tie slip on the collar much easier than it would otherwise do.

In order to more fully describe my invention, reference will be had to the accompanying drawings wherein:

Figure 1, is a plan view of a four-in-hand tie or scarf embodying one form of my

invention; Fig. 2, a side elevation thereof; 55 Fig. 3, a section on line 3^x-3^x, Fig. 1; Fig. 4, a fragmentary section on line 4^x-4^x Fig. 1, and Fig. 5, a plan view of an imperial or flowing end scarf embodying a form of my invention.

In carrying out my invention, in the form here shown, I form on the inner facing or lining of the scarf two tabs located between the neck portion (the narrow portion of the scarf adapted to pass around the collar) and the ends of the scarf a suitable distance from the ends to be conveniently grasped by the fingers and utilized in adjusting the scarf on the collar and tying it after so adjusted, or adjusting it after it is tied.

In the form of my invention shown in Figs. 1 to 4, 1 represents the inner facing or outer lining of the scarf which extends in this case substantially to the ends of the scarf, being stitched to the outer or ornamental material 2 adjacent the longitudinal edges thereof according to the usual practice in facing scarfs. This lining or facing, however, is looped or folded upon itself to form two tabs 3 and 4 which are stitched 80 transversely as at 5 and 6 to keep the loops from pulling out.

The inner lining or padding of the scarf may be formed by a strip of soft material 7 inserted between the outer or ornamental material and the inner facing 1. This lining or padding, however, constitutes no part of my invention, and since it is a well known part of scarfs, need not be further described.

In the form of the tie shown in Figs. 1 to 4, it will be seen that the tabs are not formed on the ends of the inner facing of the scarf, the latter extending beyond the tabs substantially to the ends of the scarf.

In Fig. 5, I have shown my invention as applied to an Ascot of flowing end tie or scarf in which the tabs 3' and 4' are formed on the ends of the inner facing 1', which, in this type of tie or scarf, stops shorter of 100 the ends of the tie than in the type shown in Fig. 1. Obviously, however, even in the type of scarf shown in Fig. 1, the inner facing may not extend as near the ends of the tie as shown, and the tabs may be at the end 105 of the facing as shown in Fig. 5. In any case, the tabs may be either integral with or attached to the scarf.

It will be readily seen that with scarfs of the kind here described, pulling on the outer material may be avoided by grasping the tabs instead of the ends of the scarf proper.

- 5 In fact, all of the operations of adjusting and tying the scarf may be performed with the least possible application of the hands to the outer or ornamental material of the tie. Moreover, the tabs pulling directly on the 10 inner facing and distributing the pull uniformly across such facing, causes the tie to slip longitudinally on the collar much easier than if the whole end of the tie were grasped and pulled or than if the pulling were done 15 on the inner lining or padding of the tie.

The specific cases here illustrated are but two of many forms which my invention may assume.

What I claim is:

- 20 1. A four-in-hand scarf or necktie having a neck-piece and tying ends, and free-end tabs fast to the inner facing of said tying

ends exterior to the inner sides of said ends and adapted to be grasped by the user in adjusting and tying the necktie, said tabs arranged to lie between the knot and the extreme ends of the necktie when the same is tied. 25

2. A four-in-hand scarf or necktie having a neck-piece and tying ends provided with 30 an inner facing, a free-end tab integral with said facing on each of said tying ends, said tabs being entirely exterior to the inner sides of said ends, adapted to be grasped by the user in adjusting and tying the necktie, 35 and arranged to lie between the knot and the extreme ends of the necktie when the same is tied.

In testimony whereof I affix my signature in presence of two witnesses.

WILLIAM K. MEYER.
